CODED CONTINUOUS INDUCTIVE TRAIN
CONTROL SYSTEM

Charles S. Bushnell, Rochester, N. Y., assignor to
General Railway Signal Company, Rochester,
N. Y.

Application April 1, 1941, Serial No. 386,233

10 Claims. (Cl. 246—63)

The present invention relates in general to train control systems of the coded continuous inductive type, and has more particular reference to car carried decoding apparatus for such systems.

More specifically, the invention relates to a hydraulic or fluid pressure device, responsive to coded trackway energy to decode such trackway energy and control car carried signals and the like.

In one form of the invention the decoding and control means as well as acknowledging means is constituted entirely by fluid pressure responsive means.

In a second form of the invention, the primary decoding means is pressure responsive, but the signal control means, acknowledging means, etc., include electro-magnetic means arranged to properly carry out the desired functions.

Further objects, purposes, and characteristic features of the present invention will appear as the description progresses, reference being made to the accompanying drawings showing in a purely diagrammatic manner and in no way whatsoever in a limiting sense, two forms which the invention can assume.

In the drawings:

Fig. 1 is a wholly schematic showing of one form of the invention.

Fig. 2 is a wholly schematic showing of a second form of the invention.

Referring now to the drawings, and first to Fig. 1, there is here shown trackway apparatus in general similar to the disclosure in the Hailes patent, No. 1,910,794, granted May 23, 1933; and likewise in the Reichard application Ser. No. 253,320, filed January 28, 1939.

The drawings show a stretch of single track constituted by track rails 1, with usual insulating joints 2, to form isolated track sections. At the entrance end of each section, travel being in the direction of arrow 3, is connected a track relay TR, while across the exit end is connected a track transformer T having a secondary winding in series with an adjustable resistance 4, an adjustable inductance 5, and a track battery TB. The primary winding of track transformer T is connected to a source of alternating current, here shown as of a frequency of 100 cycles per second, by way of contacts of the track relay, and contacts of a line relay LR which is controlled in a usual manner through a wire 6, by the track relay for the block next in advance.

Thus, coded energy formed by a code motor CM, which in turn is controlled by a code motor control relay CMCR, controlled through a wire 7 by the track relay next to the rear, is placed across

the exit end of each block when the block is occupied by a vehicle. The code is selected as is obvious from the drawings, and from the disclosures above referred to, in accordance with traffic conditions in advance. The control energy is coded at three different rates, 180, 120 and 75 per minute. In accordance with usual practice the block immediately to the rear of an occupied block is supplied with code at the rate of 75 impulses per minute, the block next to the rear thereof by 120 rate code, and the block next to the rear thereof and all blocks further to the rear at 180 rate code. An occupied block has its code shunted out by the wheels and axles of the occupying vehicle whereby a second vehicle entering such occupied block receives no code energy.

As shown in the drawings, the forward block is occupied by a vehicle, indicated by the wheels and axle 8, and to the rear of this vehicle, and in the same block a second vehicle is indicated by the wheels and axle 8¹ and receiver coils R, connected in the usual manner to a car carried receiving circuit tuned for 100 cycle current. This circuit includes an ampli-filter 13, the output side of which is connected to a coding primary relay CPR whereby to cause the relay to follow the code and close its contact finger 14 on its front point for every impulse of code current.

The car carried apparatus includes a code following repeater relay CFRP which can be of any usual or desired construction. It is here shown as a usual tractive type relay having a winding 15, a pivoted armature 16 biased by a spring or the like 17 to retracted position. This code following repeating relay is connected so as to be energized whenever relay CPR picks up whereby to cause its armature 16 to oscillate at the rate of the existing code.

Mechanically connected to the code following repeater relay is a pump which can be of any usual or desired form, but is here shown as a double acting pump having a pivoted operating rod 18 connected to opposed diaphragms 19 and 20, whereby to pump liquid from a supply tank S through pipe 21 and force this liquid into a pressure tank P through pipe 22. The flow of liquid is controlled in a usual manner by check valves 23, or the like.

By means of the system as described so far, it is clear that liquid is pumped from chamber 50 S to chamber P at a rate corresponding to the trackway code then in force.

The tanks S and P are separated by a partition 24 having a restricted aperture 25 therein, whereby to interconnect the tanks at a point immediately above the level of the liquid 26 when the

system is at rest; that is, when no code is present in the track rails. A restricted aperture 27 connects the upper portion of tank S to atmosphere. Leading from the upper portion of pressure tank P is a pressure pipe 28 which is employed to control car carried apparatus as will appear below.

To briefly summarize the operation of the system so far described, it should be noted that, in accordance with the rate of the code being received, pump P operates to transfer fluid from tank S to tank P and that immediately upon the pumping being initiated the level of liquid in tank P rises above aperture 25. Thereupon liquid flows back from tank P to tank S at a rate which is slower than the slowest rate of supply to the tank P at the beginning of the operation. However, as the liquid level rises in tank P and the air in the closed space above the liquid level becomes further and further compressed, the rate of flow back from tank P to tank S increases until a balance is finally reached where the level remains constant in the tank P because the volume of flow and the outflow is the same rate. This level, and the corresponding pressure above the surface of the liquid in tank P will be different for each different rate of code since the pump supplies a given volume with each stroke regardless of the back pressure. Accordingly, a pressure exists in pipe 28 leading from the upper end of tank P, which corresponds to the code rate of energy being received and which is higher or lower dependent upon whether the code rate be higher or lower.

The liquid employed in the tanks S and P can be of any suitable character, such as water or if the temperature conditions are unsuited, such as oil, or the like.

When the system is at rest, the surfaces of the liquid in the two tanks S and P are under atmospheric pressure, and the spaces above the liquid surfaces in the two tanks are unconfined, and hence the pressure in pipe 28 is substantially unchanged by changes in ambient temperature. Should the ambient temperature change during operation of the pump, under such conditions of course, the space above the liquid surface in pressure tank P, is confined, the air therein will either increase or decrease its pressure, thus to cause an increased or decreased flow of liquid back into tank S through aperture 25 to thus adjust the pressure. Accordingly, while the liquid level attained at a given code rate may differ under different temperature conditions, the resulting pressure in pipe 28 will be substantially constant at any given code rate, regardless of ambient temperature changes.

It is of course desirable that the aperture 25 remain open during operation of the system and not become clogged up to any substantial extent, and with proper inspection, and with wide enough margins between the different indications, as will appear from the following description as being entirely practical, there is small chance for any failure of the system on this count.

Connected to the pressure pipe 28 leading from the upper portion of tank P is a header tube 28¹ to which is connected a series of U-tubes, comprising tubes A, B, C and D. Each tube, such as tube A, has one end hermetically connected to the header 28¹, and the other end extending above the header and open to atmosphere as at 29. Within each U-tube is a quantity of liquid which is of a character to be electrically conductive, and one liquid which is contemplated as being employed is mercury. Any other suitable

or desirable liquid or mixture can equally well be employed.

Carried on the car is a cab signal 1S which in the present instance is shown as a light signal employing four lamps 1G, 1Y/G, 1Y and 1R which are colored respectively, green, yellow over green, yellow, and red. These lights indicate respectively, proceed, proceed prepared to pass next signal at reduced speed, proceed prepared to stop at the next signal, and stop.

Controlling signal 1S are the two U-tubes A and B, each having a series of contacts with a contact in each series, corresponding to a signal lamp. The contacts in the tube A are in the leg subjected to atmospheric pressure and are arranged downwardly from G to R, while those in tube B are positioned in the pressure subjected short leg, and are arranged reversely to that in tube A, that is, from R¹ downwardly to G¹.

Each lamp is controlled through a circuit which includes a corresponding contact in each of the two tubes A and B. For example, the system, as shown, is at rest since the receiver R is in an occupied block whereby no code is being received and the pump 1P is at rest. Under these conditions, atmospheric pressure exists in both legs of the U-tubes whereby the liquid 30, such as mercury is at the same elevation in the two legs of the tubes and is of a quantity to be just above the lowest contact in tube A, namely, contact R, and just above the highest contact in tube B, namely, R¹. Thus, the cab signal shows a red indication since the lamp 1R of the signal is energized through a circuit which includes the mercury 30 in tube A, contact R, wire 31, lamp 1R, wire 32, contact R¹, and mercury 30 in tube B.

If we assume that vehicle 8 leaves the block occupied by the vehicle having the receiver R, energy coded at the rate of 75 impulses per minute 40 is received by the vehicle in question, whereby to pump liquid from tank S into tank P at a given volume rate per minute, to thereby raise the pressure in header 28¹ to a given figure. This causes the conducting liquid in U-tubes A 45 and B to rise in the atmospheric leg and to lower in the pressure leg whereby to break the energizing circuit for lamp 1R at contact R¹ and make a like energizing circuit for lamp 1Y at contact Y.

It can be noted that, as the existing circuit is broken in tube B, the new circuit is made in tube A and should the contacts be so positioned as to cause a lapse of time between these two occurrences, a dark signal would meantime result. If on the other hand, the contacts are so arranged as to make the new circuit, before the existing circuit be broken, there would be a period of time during this overlap when the signal would display two different indications. It is contemplated that the contacts will be so positioned with respect to each other that the existing circuit will be broken at substantially the same instant that the new circuit is made or possibly that there be a short lapse of time of a few seconds during which the signal will be dark.

In a manner similar to that described above, the various aspects of the cab signal are displayed upon the receipt of the various rates of coded energy. In order that a signal shall not fail during the brief period of time when the vehicle may be passed over a crossover, or the like, and in order that a signal shall not change to a new aspect until after it is assured that this is intended as checked by several cycles of the new code occurring, it is necessary that the con-

trol means be somewhat slow acting. While in the usual relay control of vehicle apparatus, slow acting characteristics are imparted by repeater relays, and the like, in the present system this is quite unnecessary since the pressure devices employed are inherently sufficiently slow acting as to produce this desired effect.

The tubes C and D are connected to the header as are tubes A and B, and contain a conducting liquid such as mercury. The tube C has a plurality of contacts therein, positioned at different levels and corresponding with the signal aspects and designated in a descending order, as g , y/g , y and r . Like corresponding contacts in tube D are arranged in the reverse order as regards their level, namely, in an ascending order, designated as r^1 , y/g^1 , y^1 and g^1 . As with tubes A and B, the contacts in these tubes C and D are arranged respectively in the atmospheric leg and in the pressure leg.

Tube D is equipped with a check valve 31^1 of the ball type, which seats downwardly, and with a bi-pass tube 32^1 , around the check valve with a shut-off valve 33 of the gate type for preventing flow of liquid from one side of this valve to the other, or, in other words, for normally making the bi-pass 32^1 inoperative. The valve 33 constitutes a part of an acknowledging contactor Ack.C. which can be manually operated by being pushed in a direction to open valve 33 , but which normally is biased to the valve closing position by suitable means which in the present instance can be a spring biased contact finger 34 with a biasing spring 34^1 connected by an obvious circuit to a whistle valve WV, which, when deenergized, sounds a warning, and which, to be silenced, must be reenergized.

With the system at rest as shown, the two contacts r and r^1 complete an energizing circuit for whistle valve WV to maintain the whistle silent, the circuit including mercury 30 in tube C, contact r , wire 35 , contact r^1 , mercury 30 in tube D, wire 36 , contact finger 34 and back point, and the whistle valve WV.

Assume now that trackway conditions change as referred to above, so that energy coded at the 75 rate is received. Pressure will build up to a given value in header 28^1 whereby to raise the mercury level in the atmospheric leg of tube C and lower it in the pressure leg of tube D whereby to make contact with y in tube C and break contact with r^1 in tube D. The contacts are so positioned with respect to the conducting liquid that the y contact is made before the r^1 contact is broken, whereby to maintain the whistle valve energized and prevent any warning signal. It should be noted that this same operation occurs as the code changes to less and less restrictive codes ultimately to complete an energizing circuit for the whistle valve which includes the contacts g and g^1 . In this operation it can be seen the check valve 31^1 has no effect in preventing the rise of liquid level in the atmospheric leg of tube D.

Assume now that with the code rate at 180 per minute there is a change to a more restrictive code rate such as 120 per minute. The pressure in header 28^1 decreases whereby to cause the conducting liquid to drop in the atmospheric leg of tube C so as to break contact with contact g . Since the contact y/g is already made, however, unless means were provided for preventing it, the whistle valve would remain energized in the same manner as described above in connection with a change in code from more to less restric-

tive. The liquid in atmospheric leg of tube D cannot drop, however, because of check valve 31^1 and the acknowledging valve 33 whereby the liquid cannot rise in pressure leg of tube D to make the y/g^1 contact. Thus, upon contact g being broken the whistle valve is deenergized and sounds a warning which continues until the acknowledging contactor is operated to thereby open valve 33 and permit the liquid level in pressure leg of tube D to rise and find its normal level under the pressure conditions existing whereby to complete contact y/g^1 and reenergize the whistle valve and silence it.

The operation in each of the changes from less to more restrictive conditions is the same as just described. In each case the whistle valve is sounded to apprise the engineer that conditions have become more restrictive and that he should be alert, and this is assured, and his requirement that he complete the acknowledging act required in order to silence the signal.

In the acknowledging system of this form of invention, if the contacts are so arranged that upon passing from r to y , for example, the contact r^1 is broken before the contact y is made, the whistle sounds until contact y is made. If the contacts are so arranged there is a resulting short blast of the signal device on going to less restrictive conditions, for apprising the engineer that a change in traffic conditions has occurred, but this blast can be made so short as to not require the acknowledging act.

If, however, the contacts are so arranged as to have contact r^1 broken simultaneously with the making of contact y or even slightly later, then when contact y is made, there is no operation of the whistle on changes to more favorable conditions.

The acknowledging contactor can of course be remotely controlled by any usual mechanical or electrical means, the essential feature being that some act on the part of the engineer is required upon every change to more restrictive conditions to silence the whistle or remove any other penalty, such as a brake penalty, or the like.

The system as thus far described involves car carried apparatus and employs but two relays, one of which operates the pump and does not have the usual relay function of passing electrical energy on to a further instrumentality.

It should be noted that a code following relay CFR is employed but this relay is not essential and could be eliminated entirely under certain conditions whereupon the code following repeater relay would have its windings connected directly to the output side of the ampli-filter.

Referring now to Fig. 2, which shows a modified form of the present invention, there is here shown a pressure tube 27^1 which corresponds to the tube 28 of the form of invention shown in Fig. 1. In the form of invention of Fig. 2, the trackway apparatus and pumping system, together with the supply tank and pressure tank, can be identical with what has already been disclosed. Thus, pressure exists in tube 27^1 in accordance with whether any code is in force and with what particular code is in force. In other words, the pressure in tube 27^1 is atmospheric pressure under danger conditions or when the system is not cut into service and is above atmospheric to various degrees in accordance with whether the code is relatively slow or fast.

In this form of invention there is a pressure chamber P^1 which contains air at atmospheric pressure if there be no code present, and at high-

er pressures as any code present increases in its rate. Associated with the pressure chamber are three code responsive pressure relays 75R, 120R and 180R all constructed in substantially the same way.

Considering the structure of relay 75R, for example, it is constituted by a diaphragm 36 subjected to the pressure of the pressure chamber on one side and to that of a biasing spring 37 on the other side. It has a stem 38 connected to the diaphragm and in turn connected to a contact finger 39 by means of a pin 40, the finger being pivoted at 41. When the pressure in chamber P¹ is atmospheric the diaphragm assumes the position shown and the contact finger 39 makes up its back point.

Upon the slow rate code of 75 being received the pressure in the chamber P¹ builds up to a point sufficient to overcome the bias of spring 37 whereby the diaphragm moves downwardly, and contact finger 39 makes up its front point.

In like manner relay 120R moves from its shown biased position to its operated position for making up its front point upon the 120 rate code being present. In like manner, the 180R relay is responsive to the 180 rate code, it being noted that the spring tension of the 180R relay is greater than that of the 120R relay and this latter, greater than the 75R relay, due to any convenient or desired adjusting means such, for example, as the two spacing washers 42 and 43. Thus, with relay 120R there is the single spacing washer 43, while with relay 75R there is no spacing washer. Accordingly, the spring bias on the three relays increases from the 75R relay to the 180R relay. The adjusting means shown is merely one example of what can be employed, it being contemplated that any other means, such as a threaded traveling nut, a cam, or the like, can be employed.

The various circuits and instrumentalities employed in connection with these three decoding pressure responsive relays can be of the type disclosed in the W. D. Hailes patent, Reissue 19,599 of June 4, 1935, and accordingly, merely a brief description of the circuits is deemed sufficient for the present disclosure.

A series of repeating relays 2G, 2Y/G, 2Y and 2R is employed and each of these relays has an energizing circuit including a back point of each of the other three relays, in series, and, in addition, these energizing circuits are closed, respectively, when all three of the pressure responsive relays are picked up; when pressure responsive relay 180R is released and the other two pressure responsive relays are picked up; when the pressure responsive relays 180R and 120R are released, and the pressure responsive relay 75R is picked up; and when the three pressure responsive relays are all released. For example, under the conditions shown in Fig. 2, where no code is being received, all of the pressure relays are in released position and the 2R relay is picked up through a circuit including contact finger 39 and back point of relay 75R, wire 44, relay 2R, the three contact fingers 45, 46 and 47 and back points of relays 2Y, 2Y/G and 2G respectively, and the wires 48, 49, 50 and 51.

The cab signal employed in this form of the invention is also of the four aspect type and the indications are the same as described above in connection with Fig. 1. The circuits for energizing the lamps of the cab signal are obvious from the drawings, it being noted that the lamp R² is energized through a circuit including con-

tact finger 52 and front point of relay 2R. In like manner, the other lamps as G² are energized through circuits controlled by the corresponding contact fingers as contact finger 53 of relay 2G.

Associated with the three relays 2Y/G, 2Y and 2R are three stick relays 2Y/GS, 2YS and 2RS each of which has a stick circuit including a contact finger and front point of its corresponding control relay. The first two of the relays have pick-up circuits including contact fingers and front points of the next referred to relay in its own series. For example, relay 2Y/GS has a pick-up circuit including contact finger 54 and front point of relay 2YS. Likewise, relay 2YS has a pick-up circuit including contact finger 55 and front point of relay 2RS. The pick-up circuit for relay 2RS passes through an acknowledging contact finger 56 of an acknowledging contactor Ack.C., whereby it is necessary to operate the acknowledging contactor in order that relay 2RS be picked up.

Employed in this system is a whistle valve WV² which sounds when energized and is silent when deenergized, and this whistle valve can receive energy when the relay 2Y/GS is in retracted position, and any one of the three relays 2R, 2Y and 2Y/G is in attracted position or when the acknowledging contactor is depressed so as to make up acknowledging contactor finger 57 with its back point.

Under the traffic conditions illustrated in Fig. 2, relay 2R is energized to close its contact finger 58 on its front point but since relay 2Y/GS is in attracted position, the whistle valve is deenergized and hence is silent.

The circuits are so arranged that, as the code changes from more to less restrictive, that is, from no code up toward the 180 rate code, the relays 2Y, etc., pick up, and the relay 2Y/GS remains up, since these relays are sufficiently slow to release to bridge over momentary deenergized periods. Thus, as the conditions on the trackway change from more to less restrictive, the whistle valve is maintained deenergized, and hence silent.

On a change of traffic conditions to more restrictive, each change results in the whistle valve becoming energized and requires operation of the acknowledging contactor Ack.C. to deenergize it before it is silenced. For example, should the code in force be the 180 rate, the lamp G² is lighted and the relay 2G is energized, and all of the stick relays 2RS, etc., are deenergized so that the whistle valve circuit is closed at contact finger 59 and back point of stick relay 2Y/GS, but is open at the three front points of the three relays 2R, 2Y and 2Y/G.

Assume now that the code changes to a more restricted one such as the 120 rate. In these circumstances, the pressure responsive relay 180R releases its contact finger to thereby pick up relay 2Y/G and change the signal aspect to approach restricting by lighting the lamp Y/G². The whistle valve is energized through a circuit including wires 60, 61, contact finger 62, and front point of relay 2Y/G, wires 63, 64 and 65 and contact finger 59 and back point of relay 2Y/GS.

To silence the whistle valve, the acknowledging contactor must be depressed whereby to pick up relay 2RS through its pick-up circuit which includes acknowledging contactor finger 56 and back point. With relay 2RS picked up, relays 2YS and 2Y/GS pick up in the order named

with relay 2Y/GS sticking up through its stick circuit which includes contact finger 66 and front point of relay 2Y/G. This opens the whistle valve circuit at contact finger 59 and silences the whistle. The acknowledging contactor can now be released.

The acknowledging contactor is constructed to avoid its misuse by having the contactor finger 57 so arranged that, when the contactor is depressed, the whistle valve is energized through this contact finger 57 and its back point, this protective energizing circuit including wires 67 and 68.

From the above it can be seen that, in the form of invention shown in Fig. 2, and described just above, the same functions are carried out as in connection with the form of invention described in connection with Fig. 1. Acknowledgment is required only upon a change to more restrictive conditions and the system depending primarily for its functions on hydraulic, or other fluid means, for influencing pressure responsive devices to decode the coded trackway control energy.

It is to be understood that this specification contemplates such variations and modifications as may occur desirable or practical from time to time without departing from the spirit of the invention disclosed herein.

The above rather specific description of two forms of the present invention has been given solely by way of example, and is not intended in any manner whatsoever in a limiting sense. All such variations and modifications as may be made from time to time are intended to be covered by this application insofar as they are not specifically excluded therefrom by a reasonable interpretation of the scope of the appended claims.

Having described my invention, I now claim:

1. In a train control system for railways, in combination with means for placing, on a trackway, control energy variously coded in accordance with traffic conditions ahead, a receiver positioned to receive the control energy, pressure producing means, an operative connection between the receiver and the pressure producing means to control the latter to produce various pressures in accordance with the respective energizations of the receiver, a plural aspect signal, circuit means for controlling the signal, and means in the circuit means respectively controlled by said various pressures produced by the pressure producing means, for causing the signal to display various signal aspects.

2. In train control systems for railways, in combination, a stretch of track divided into electrically isolated sections, means for placing coded control energy, coded variously in accordance with traffic conditions ahead, on the trackway, a receiver positioned to be energized by the control energy, a plural aspect signal, circuit means for distinctively controlling the signal, a pressure producing device operatively connected to the receiver for producing various pressures in accordance with the respective codes energizing the receiver, and contacts in the circuit means respectively controlled by said various pressures, for causing the signal to display various signal aspects.

3. In train control systems for railways, in combination, a stretch of track divided into electrically isolated sections, means for placing coded control energy, coded variously in accordance with traffic conditions ahead, on the

trackway, a receiver positioned to be energized by the control energy, a plural aspect signal, circuit means for distinctively controlling the signal, pressure producing means operatively connected to the receiver for producing various pressures in accordance with the respective codes energizing the receiver, the pressure producing means comprising, a pump, an atmospheric chamber open to atmosphere, a pressure chamber, means interconnecting the two chambers, a connection from the atmospheric chamber to the pump input, and a connection from the pump output to the pressure chamber, and contacts in the circuit means respectively controlled by said various pressures in said pressure producing means for causing the signal to display various signal aspects.

4. In train control systems for railways, in combination, a stretch of track divided into electrically isolated sections, means for placing control energy, coded variously in accordance with traffic conditions ahead, on the trackway, a receiver positioned to be energized by the control energy, a plural aspect signal, circuit means for distinctively controlling the signal, a pressure producing device operatively connected to the receiver for producing various pressures in accordance with the respective codes energizing the receiver, the pressure producing device comprising, a pump, an atmospheric chamber open to atmosphere, a pressure chamber, means interconnecting the two chambers, a connection from the atmospheric chamber to the pump input, and a connection from the pump output to the pressure chamber, a U tube communicating at one side with the pressure chamber and at the other side with atmosphere, electrically conducting fluid in the tube, and contacts positioned in the tube at various levels and included in said circuit means and effective, respectively in accordance with said various pressures, for causing the signal to display various signal aspects.

5. In train control systems for railways, in combination, a stretch of track divided into electrically isolated sections, means for placing coded control energy coded variously in accordance with traffic conditions ahead on the trackway, a receiver positioned to be energized by the control energy, a signal having plural aspect signal means to display a plurality of aspects, circuit means for distinctively controlling the signal, a pressure producing device operatively connected to the receiver for producing various pressures in accordance with the respective codes energizing the receiver, contacts in the circuit means made variously effective, respectively, in accordance with the various pressures in said device, for causing the signal to display various signal aspects, the pressure producing device comprising, a pump, an atmospheric chamber open to atmosphere, a pressure chamber, means interconnecting the two chambers, a connection from the atmospheric chamber to the pump input, and a connection from the pump output to the pressure chamber, two U tubes, each with one leg open to atmosphere and the other leg connected to the pressure chamber, said contacts including a pair of contacts for each signal aspect means with one of each pair in the atmosphere leg of one tube and the other in the pressure leg of the other tube, and electrically conducting fluid in the two tubes.

6. In train control systems for railways, in combination, a stretch of track divided into electrically isolated sections, means for placing

control energy, coded variously in accordance with traffic conditions ahead, on the trackway, a receiver positioned to be energized by the control energy, a signal having plural aspect signal means to display a plurality of aspects, circuit means for distinctively controlling the signal, a pressure producing device operatively connected to the receiver for producing various pressures in accordance with the respective code energizing the receiver, contacts in the circuit means operated respectively in accordance with the various pressures in said device for causing the signal to display various aspects, the pressure producing device comprising, a pump, an atmospheric chamber open to atmosphere, a pressure chamber, means interconnecting the two chambers, a connection from the atmospheric chamber to the pump input, and a connection from the pump output to the pressure chamber, two U tubes, each with one leg open to atmosphere and the other leg connected to the pressure chamber, said contacts including a pair of contacts for each signal aspect means with one of each pair in the atmosphere leg of one tube, and the other of each pair in the pressure leg of the other tube, and electrically conducting fluid in the two tubes, the two contacts of each pair in the two tubes being arranged in reverse order, in elevation, in the two tubes and the two contacts of each pair for each signal aspect means being connected in series with each other and with its signal aspect means.

7. In train control systems for railways, in combination, a stretch of track divided into electrically isolated sections, means for placing control energy, coded variously in accordance with traffic conditions ahead, on the trackway, a receiver positioned to be energized by the control energy, a signal having plural aspect signal means for displaying a plurality of signal aspects, varying in restrictiveness, circuit means for distinctively controlling the signal, a pressure producing device operatively connected to the receiver for producing various pressures in accordance with the respective codes energizing the receiver, contacts in the circuit means operated, respectively, in accordance with the various pressures for causing the signal to display various signal aspects, the pressure producing device comprising, a pump, an atmospheric chamber open to atmosphere, a pressure chamber, means interconnecting the two chambers, a connection from the atmospheric chamber to the pump input, and a connection from the pump output to the pressure chamber, two U tubes each with one leg open to atmosphere and the other leg connected to the pressure chamber, said contacts including a pair of contacts for each signal aspect means with one contact of each pair in the atmosphere leg of one tube and the other of each pair in the pressure leg of the other tube, electrically conducting fluid in the two tubes, a normally inactive penalty means, manually operative acknowledging means, and pressure controlled means connected to the pressure chamber and operative to make the penalty means active upon a change in signal aspect to a more restrictive one, until after operation of the acknowledging means.

8. In train control systems for railways, in combination, a stretch of track divided into electrically isolated sections, means for placing control energy, coded variously in accordance with traffic conditions ahead, on the trackway, a re-

ceiver positioned to be energized by the control energy, a signal having plural aspect signal means for displaying a plurality of signal aspects varying in restrictiveness, circuit means for distinctively controlling the signal, a pressure producing device operatively connected to the receiver for producing various pressures in accordance with the respective codes energizing the receiver, contacts in the circuit means operated respectively in accordance with the various pressures in said device for causing the signal to display various aspects, the pressure producing device comprising, a pump, an atmospheric chamber open to atmosphere, a pressure chamber, means interconnecting the two chambers, a connection from the atmospheric chamber to the pump input, and a connection from the pump output to the pressure chamber, two U tubes, each with one leg open to atmosphere and the other leg connected to the pressure chamber, said contacts including a pair of contacts for each signal aspect means with one contact of each pair in the atmosphere leg of one tube and the other in the pressure leg of the other tube, electrically conducting fluid in the two tubes, the corresponding contacts in the two tubes being arranged in reverse order as to their elevation in the two tubes, the two contacts for each signal aspect means being in series with each other and the signal aspect means, a normally inactive penalty means, manually operative acknowledging means, and pressure controlled means connected to the pressure chamber and operative to make the penalty means active upon a change in signal aspect to a more restrictive one, until after operation of the acknowledging means.

9. In train control systems for railways, in combination, a stretch of track divided into electrically isolated sections, means for placing control energy, coded variously in accordance with traffic conditions ahead, on the trackway, a receiver positioned to be energized by the control energy, a plural aspect signal, circuit means for distinctively controlling the signal, a pressure producing device operatively connected to the receiver for producing pressures varying in accordance with the particular code energizing the receiver, a plurality of contacts in the circuit means, elastic means biasing the contacts to differing degrees, a pressure responsive means operatively connected to each contact, and means communicating each pressure responsive means with the pressure in the pressure producing device.

10. In train control systems for railways, in combination, a stretch of track divided into electrically isolated sections, means for placing control energy, coded variously in accordance with traffic conditions ahead, on the trackway, a receiver positioned to be energized by the control energy, a plural aspect signal, circuit means for distinctively controlling the signal, a pressure producing device operatively connected to the receiver for producing pressures varying in accordance with the code energizing the receiver, a plurality of contacts in the circuit means, spring means biasing each of the contacts to differing degrees, a diaphragm operatively connected to each contact, and means subjecting each diaphragm to the pressure in the pressure producing device for distinctively controlling the signal.

CHARLES S. BUSHNELL.
